UNITED STATES PATENT OFFICE.

OTTMAR MERGENTHALER, OF BALTIMORE, MARYLAND, ASSIGNOR TO THE
OTT. MERGENTHALER COMPANY, OF SAME PLACE.

MACHINE FOR STRAIGHTENING METAL STOCK.

SPECIFICATION forming part of Letters Patent No. 636,912, dated November 14, 1899.

Application filed May 11, 1898. Serial No. 680,397. (No model.)

To all whom it may concern:

Be it known that I, OTTMAR MERGENTHALER, a citizen of the United States, residing at Baltimore, in the State of Maryland, have 5 invented certain new and useful Improvements in Machines for Straightening Metal Stock, of which the following is a specification.

My invention relates especially to that class of straightening-machines wherein the stock 10 or metal to be straightened is passed between suitably-rotated rolls under pressure.

It sometimes happens as the stock is delivered from the rolling-mills that it is not exactly of the thickness which may be required 15 and that to reduce it to this required thickness it has to be passed through an accurately-adjusted rolling-mill, which latter operation sometimes has the effect of slightly bending the stock in an irregular way and in many instances 20 leaves it with quite sharp bends or wrinkles in it. In order to straighten out the stock, it has been customary at this stage of the operation to pass it through a straightening-machine provided with suitably-actuated 25 rolls, the effect of this being to partially remove the wrinkles or bends in the stock. Owing to the great pressure that is required for this operation, it will be obvious that the rolls must possess great strength and rigidity 30 not only in themselves, but in their bearings, and consequently it has been customary to provide large rolls of considerable diameter strongly and suitably journaled at their ends. In the use of the class of machines just de- 35 scribed it frequently happens that owing to the large diameter of the rolls they fail to straighten out the short bends or wrinkles previously referred to. In order to obviate the objection last named, it has been proposed 40 to make the rolls of much smaller diameter; but in the use of such rolls an objection has arisen in the fact that owing to the great pressures to which they are subjected these smaller rolls have not sufficient rigidity to 45 withstand the strain and that in the course of operation these rolls when journaled at their ends are either broken or bent, thereby defeating the purposes of the machine. Accordingly I have devised a form of straightening-machine provided with small rolls which in place of being journaled at their

ends are supported throughout the operative length of the rolls in longitudinal bearings; thereby insuring absolute rigidity during the operation of straightening the stock.

55

Referring to the drawings, Figure 1 is a front view of a portion of my improved straightening-machine, partly in section, on the line 1 1 in Fig. 2. Fig. 2 is a side view of a portion of my improved machine, partly in section, 60 on the line 2 2 in Fig. 1. Fig. 3 is a sectional detail taken substantially on the line 3 3 in Fig. 2.

The frame of the machine, P, may be of any desired form, provided only it possesses sufficient strength and rigidity to sustain the operating parts. Power is transmitted from any suitable source to the band-pulley A, fast on the short shaft B, suitably journaled in the brackets P³ P³ of the frame P. Fast upon the 70 short shaft B is the elongated pinion B', from which motion is transmitted by the gearing hereinafter described to the various rolls. Also journaled in the brackets P³ are the short shafts C', D', E', F', and G', (see Fig. 3,) to 75 which are respectively attached the driven pinions C, D, E, F, and G. As shown in Figs. 2 and 3, the shafts C' and D' are so located that their respective pinions C and D mesh into and are turned by the pinion B' at the 80 rear portion of said pinion B'. The shaft G' is centrally located, and the pinion G is so placed thereon that it meshes into and is turned by the front portion of the pinion B'. It will be obvious from this that the pinions 85 C, D, and G, and consequently the shafts C', D', and G', are rotated in the same direction. The shafts E' and F' are located over the shafts C' and D', and the pinions E and F, carried thereby, are so located that they mesh into and 90 are turned by the pinions C and D, respectively, thereby effecting a rotation of the shafts E' and F' in a direction opposite to that of the shafts C', D', and G'.

The front of the machine is provided with 95 a solid base-plate P', in which are formed the bearings Q Q Q for the lower rolls. These bearings are, as shown in the drawings, simply long grooves so shaped and arranged as to receive the rolls and to support and hold 100 them firmly in position and to afford a rigid bearing for them throughout their entire op-

erative length, thereby entirely doing away with the possibility of the rolls being bent during the operation of straightening. The plurality rolls C³ D³ G³ are arranged in a plane and are flexibly connected by the respective joints or couplings C² D² G² to the shafts C' D' G', whereby, as previously described, the three lower rolls will be rotated in the same direction.

- 10 Located in the guideway J', formed in the bracket P² of the frame P, is the sliding block or plunger J, which in effect constitutes the press proper, which imparts the necessary pressure to the rolls during the operation of straightening. Suitably journaled to turn in the bracket P² is the screw K, attached to the plunger J and provided with the wheel L, whereby the plunger J may be moved to give the necessary pressure to the parts in the manner well understood in the art. Formed in the lower surface of the plunger J are the bearings Q' Q', which are so shaped as to receive and hold the rolls E³ and F³ and to afford a continuous bearing for the rolls, whereby 25 they are supported and held throughout their operative length and given the required rigidity in the same manner that the lower rolls are held and supported in the bearings Q. The rolls E³ and F³ are arranged in a plane 30 parallel to the plane of rolls C³ G³ D³ and are flexibly connected by the joints or connections E² F², respectively, to the shafts E' and F', whereby they are given a direction of rotation opposite to that of the lower rolls. Also located on the base-plate P' are guides H H for 35 guiding and directing the work passed between the rolls. The rolls in each set are arranged alternately with respect to the rolls of the opposite set.
- 40 Having described the construction and arrangement of the various parts, their operation will be understood to proceed in the following manner: Power being imparted to the band-pulley A through the connections previously described, the lower rolls and the 45 upper rolls will be operated in opposite directions, respectively, in such manner as to feed the work X therethrough. The desired degree of pressure or opening between the

rolls is secured by adjusting the plunger J, 50 and the work X is then introduced between the guides H H and between and through the rolls, which will remove the bends or irregularities therefrom.

I have found in practice that this construction and arrangement of rolls of small diameter supported in bearings throughout their operative length overcomes all the difficulties and objections previously described as arising from the employment of rolls not supported 60 throughout their operative length and that not only are the small wrinkles and irregularities entirely removed from the stock, but also that the rolls themselves are not bent nor broken. 65

Although I have shown and described a preferred embodiment of my invention in this application, it will be understood that many changes may be made therein without departing from the spirit of my invention. 70

Having described my invention, what I claim, and desire to secure by Letters Patent, is—

1. In a machine for straightening metal stock, the combination of two opposing sets 75 of rolls, and two opposing bearing-blocks adjustable relatively, the rolls having bearings in said blocks constructed to support them throughout their operative lengths, and means for adjusting the bearing-blocks relatively, 80 for the purpose set forth.

2. In a machine for straightening metal stock, the combination of two opposing sets of rolls, each set comprising a plurality of rolls located in a common plane, two bearing-blocks in which the rolls have bearings constructed to support them throughout their operative lengths, gearing arranged to drive the several rolls of the sets, and flexible connections between said rolls and the gearing, 85 substantially as described.

In testimony whereof I affix my signature in presence of two witnesses.

OTT. MERGENTHALER.
